Primary Examiner — Rebecca Tsehay(74) *Attorney, Agent, or Firm* — Patterson Thuente IP(57) **CLAIM**

We claim the ornamental design for an aerosol generator, as shown and described.

DESCRIPTION

FIG. 1 is a top perspective view of an aerosol generator.

FIG. 2 is a top view of the aerosol generator depicted in FIG. 1.

FIG. 3 is a bottom view of the aerosol generator depicted in FIG. 1.

FIG. 4 is a front view of the aerosol generator depicted in FIG. 1.

FIG. 5 is a rear view of the aerosol generator depicted in FIG. 1.

FIG. 6 is a right side view of the aerosol generator depicted in FIG. 1.

FIG. 7 is a left side view of the aerosol generator depicted in FIG. 1; and,

FIG. 8 is a bottom perspective view of the aerosol generator depicted in FIG. 1.

The broken lines in the drawings illustrate portions of the aerosol generator that form no part of the claimed design.
